UNITED STATES PATENT OFFICE.

EDWARD HENRY JOHNSON AND ARTHUR HENRY WINTERTON, OF EAST RAND,
TRANSVAAL, SOUTH AFRICA.

CONCENTRATOR.

Application filed October 21, 1925, Serial No. 63,913, and in the Union of South Africa October 22, 1924.

The purpose of the present invention is to provide apparatus adapted to withdraw concentrate continuously from a stream of ore pulp, which does not require skilled attention, and which may thus advantageously be substituted for the present amalgamating or concentrating tables.

The invention provides a drum arranged with its axis horizontal or somewhat inclined, the pulp stream being caused to flow through the lower part of the drum. The interior surface of the drum is of a suitable character to retain concentrate deposited from the pulp. The drum is slowly revolved so as to withdraw the deposited concentrate from the pulp and carry the same up the ascending side of the drum, whence it is suitably collected.

A perspective view with parts broken away, of one form of apparatus according to the invention is illustrated in Fig. I of the accompanying drawings; Fig. II shows a detail of one form of concentrating surface.

25 2 indicates the drum into which the pulp to be treated is fed by such means as the distributing launder 3. The treated pulp is discharged from the end 4 of the drum into a launder or the like 5. The drum is so set that the pulp flows through it at the desired rate, an inclination of six degrees at its lower surface having been found suitable for the treatment of tube mill effluent. The concentrate adheres to the surface of 30 the drum and is carried up the rising side of the drum (indicated by the arrow A) away from the pulp, being preferably washed by liquid distributed from the perforated pipe 7.

40 For collecting the concentrate there is shown a hopper 8 which extends for the length of the drum and has an open mouth or top 9 into which the concentrate is received. The concentrate is, when necessary, detached from the drum surface by any appropriate means such as jets of water directed from a perforated pipe 10 onto the drum surface over the hopper mouth.

45 Provision may be made for adjusting the position of the hopper mouth about the surface of the drum, to bring it to the position at which the concentrate is most readily or conveniently displaced from the drum surface. For this purpose the hopper is 50 provided with trunnions 11 co-axial with the drum and mounted in end frames 12.

The hopper is clamped at any desired angular position by means of an arm 13 extending from it and clamped to a fixed slotted quadrant 14.

60 The bottom of the hopper is narrowed and steeply inclined to cause the concentrate to flow off into a launder 15.

65 Rotation of the drum is effected by any suitable means such as a belt 16 passed about it. The rotational speed is adjusted to the rate at which it is desired to withdraw concentrate from the pulp stream; a speed of five revolutions per minute having been found suitable for tube mill effluent 70 pulp.

75 The interior surface of the drum is such as to retain the concentrate against the flow of the pulp stream and also to elevate it. In some cases there is used a surface material, such as grease, to which the concentrate adheres more readily than does the gangue material. In other cases the retention of the concentrate is due to the mechanical formation of the surface. The drawings show a 80 rifled surface specially adapted for the purpose of the invention. The ripples 17 are disposed at an angle so that to a substantial extent they oppose both the tendency for longitudinal movement due to the scour and 85 the slipping movement, at right angles to it, due to gravity. Their angular disposition is preferably such that they rise from the intake end of the drum on the rising side thereof.

90 This form of surface has been found suitable for metalliferous concentrates. It may conveniently be formed on a rubber sheet 18, a portion of which is shown to an enlarged scale in Fig. II. Said sheet may be fixed to 95 the wooden lining 19 of the drum.

We claim:—

In a concentrator, the combination of a rotatable drum, means to rotate the same in one direction, means to pass material to be 100 treated into the drum at one end, the material being discharged from the other end of the drum, the internal surface of the drum having ripples inclined inwardly and upwardly from the intake end of the drum on 105 the rising side thereof, and means to collect concentrate from the surface of the drum.

In testimony whereof we affix our signatures.

EDWARD HENRY JOHNSON.
ARTHUR HENRY WINTERTON.
